(57) **CLAIM**

The ornamental design for a wallet for securing onto one's body, as shown and described.

DESCRIPTION

FIG. 1 is a rear elevational view of a wallet for securing onto one's body.

FIG. 2 is a front elevational view thereof.

FIG. 3 is a top plan view thereof, the bottom plan view being a mirror image of the top plan view; and,

FIG. 4 is a left side elevational view thereof, the right side elevational view being a mirror image of the left side view.
